UNITED STATES PATENT OFFICE.

MARK E. HUNTER, OF ALLEGHENY, PENNSYLVANIA.

CLAMP.

SPECIFICATION forming part of Letters Patent No. 768,281, dated August 23, 1904.

Application filed January 6, 1904. Serial No. 187,877. (No model.)

To all whom it may concern:

Be it known that I, MARK E. HUNTER, a citizen of the United States, residing at Allegheny, in the county of Allegheny and State 5 of Pennsylvania, have invented a new and useful Improvement in Clamps, of which improvement the following is a specification.

This invention relates to an improved clamp for glass-constructed show-cases; and it consists in the certain details and arrangement of parts, as will be fully described hereinafter.

In the accompanying drawings, Figure 1 is a perspective view of my improved clamp, the same showing the construction and arrangement of the invention. Fig. 2 is a sectional plan view taken through one of the angles of a glass show-case, showing my improved clamp in position thereon. Fig. 3 is a sectional side elevation of the same. Fig. 4 is a face view 20 of the washer.

To put my invention into practice, I form from cast metal a body portion 1, having a recess formed by two parallel walls 1' on the one side and a similar recess 2, formed by the 25 walls 2' and 4, the whole being joined together by a semicircular integral portion 3. Formed at the end of the wall 4 is a threaded opening for the reception of a short screw 5 formed with a head 6. A flat washer (see Fig. 30) 4) is provided, the same consisting of a body portion 9, having a recess 10, adapted to engage with the semicircular portion 3 of the clamp and hold the said washer in position.

In operation the front glass 7 is inserted in 35 the recess 1, the said recess being formed to fit neatly about the glass. The other plate, 7', is inserted in the recess 2, the washer 9 placed

in position, and the screw 5 operated to clamp the said plate firmly therein.

By this construction and arrangement of a 40 clamp it is not necessary to drill holes in the glass for rivets, as is now the common practice, and it is obvious that the recesses for the reception of the plates of glass may be arranged at any angle the one with the other and that 45 slight modifications and changes may be made in the details of construction without departing from the spirit of the invention.

Having thus described my invention, what I claim, and desire to secure by Letters Patent, is—

1. A clamp for glass-constructed show-cases or other purposes, consisting of a body portion having recesses for the reception of the plates of glass, the one recess at an angle with 55 the other, a screw 5 entering one of said recesses and a suitable washer 9, whereby the clamp may be fixed to one of the plates.

2. A clamp for attaching plates of glass together, consisting of the body portion 1, having recesses 1' and 2, the one recess arranged at an angle with the other, the semicircular connecting-piece 3, the screw 5, the washer 9, having a recess 10, adapted to engage with the portion 3, all arranged and combined for 60 service, substantially as described.

In testimony whereof I have hereunto signed my name in the presence of two subscribing witnesses.

MARK E. HUNTER.

In presence of—

M. HUNTER,
MAX W. KURNIKER.
